(57) **CLAIM**

The ornamental design for a package having an icon, as shown and described.

DESCRIPTION

FIG. 1 is a perspective view of a package having an icon embodying our new design;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is bottom view thereof;

FIG. 8 is a perspective view of a second embodiment of a package having an icon embodying our new design;

FIG. 9 is a front view thereof;

FIG. 10 is a left side view thereof;

FIG. 11 is a rear view thereof;

FIG. 12 is a right side view thereof;

FIG. 13 is a top view thereof; and,

FIG. 14 is bottom view thereof.

In the drawings, the broken lines depict environmental subject matter only that forms no part of the claimed design.

1 Claim, 6 Drawing Sheets
